A. E. OSTRANDER.
CAR BOLSTER AND SIDE BEARING.
APPLICATION FILED DEO. 30, 1910.

1,042,470.

Patented Oct. 29, 1912.

UNITED STATES PATENT OFFICE.

ALLEN E. OSTRANDER, OF RIDGEWOOD, NEW JERSEY, ASSIGNEE TO AMERICAN CAR AND FOUNDRY COMPANY, OF ST. LOUIS, MISSOURI, A CORPORATION OF NEW JERSEY.

CAR-BOLSTER AND SIDE BEARING.

1,042,470.

Specification of Letters Patent. Patented Oct. 29, 1912.

Application filed December 20, 1910. Serial No. 606,014.

To all whom it may concern:

Be it known that I, ALLEN E. OSTRANDER, residing at Ridgewood, Bergen county, New Jersey, and being a citizen of the United States, have invented certain new and useful Improvements in Car-Bolsters and Side Bearings, of which the following is a full, clear, and exact description, such as will enable others skilled in the art to which it applies to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a transverse vertical sectional view through a portion of a tank car and illustrating in elevation a bolster constructed with the invention applied thereto, parts of said bolster being shown in section for better illustrating the invention. Fig. 2 is an enlarged vertical sectional view taken on the plane of line 2—2 of Fig. 1 and looking in the direction of the arrows.

The object of the invention is to provide a bolster construction for cars which is adapted to support the weight of the superstructure and of the lading carried thereby at points directly above, or in the lines of greatest compression above, the side bearings of the bolster, and further to form said side bearings with means for strengthening the vertical members of the bolster along said lines of compression and thus to render possible the lightening of the greater portions of the bolster without detracting from its sustaining qualities.

A further object is to provide, in combination with the above, means formed upon each of the side bearings adapted to serve as an anchor member for the car body.

It is obvious that the invention is equally applicable to any class of cars wherein the body structure is independent of and is supported upon the bolsters.

In the drawings I have illustrated the invention as being applied to a tank car, but I do not wish to be understood as limiting myself to the accepted forms of car bodies common to tank cars.

Referring to the parts by numerals, 1—1

indicates the center sills of the underframe and 2 the tank of ordinary tank car construction.

It will be understood that the center sills extend longitudinally beneath the tank and 60 that the bolsters, with which the invention is particularly concerned are disposed transversely of the center sills in their usual positions adjacent opposite ends of said sills.

The bolsters are obviously identical and 65 each is composed of spaced flanged diaphragms as 3—3 disposed one pair upon each side of the center sills and connected by the usual top and bottom cover plates 4 and 5, which cover plates extend transversely of the car above and below the center sills. The top and bottom flanges of the diaphragms are turned outwardly and the cover plates 4 and 5 are riveted thereto and to the top and bottom flanges of the center 70 sills, all of which is common in the art. The usual filler casting as 6 and the center bearing plate as 7 are also illustrated.

Fixed to the upper surface of the top cover plate 4, at points spaced upon opposite sides of the center sills, are supporting castings 8—8. Out-turned flanges as 9—9 are formed upon the lower edge of each of the castings 8 and said flanges are fixed to the cover plate 4 by some of the rivets which 80 serve to connect said cover plate to the top flanges of the diaphragms 3. The upper surface of each of the castings 8 is curved to correspond with the curvature of the tank, or preferably to correspond to the curvature 85 of a tank of the largest possible diameter, and said curved surface is formed with a series of pockets or recesses as 10—10 adapted each to receive a block as 11 of cast iron, or of any suitable material. The several 90 blocks 11 are so proportioned and their upper surfaces so curved as to conform collectively to the curvature of a given size of tank. A larger or a smaller tank will require blocks of slightly different shape and 95 relative proportions.

Fixed to the bottom flanges of the diaphragms 3 at points spaced upon opposite sides of the center sills, are the side bearings 100 as 12—12, each of which extends transversely of the bolster from the outer edge of the lower flange of one of the diaphragms 3 to the outer edge of the lower flange of the adjacent diaphragm 3. The opposite ends of the bottom cover plate 5 extend only to the 110

inner side of the adjacent side bearings and each of said bearings is formed with a flange 13 projecting under the end portion of said cover plate and fixed thereto by some of the 5 rivets as 14 which fix said cover plate to the flanges of the diaphragm. Other rivets as 14^a extend only through said flange and through said cover plate between the webs of the diaphragms.

10 Upon the side opposite the flange 13, each of the side bearings is formed with a flange 15 which flange is fixed at its opposite ends directly to the under faces of the adjacent lower flanges of the diaphragms 3 by rivets 15 as at 16. Intermediate the webs of the diaphragms each of the flanges 15 is suitably reinforced and apertured as at 17 and adapted to serve as an anchor for the adjacent end of the usual tank bands as 18, which is extended through said aperture and held by 20 a nut as at 19.

It should be noted that the flange 15 may serve in a similar capacity as an anchor receiving member for anchoring a car body of 25 any design suggested hereinbefore.

25 Formed integral with each of the side bearings 12 is an upwardly projecting portion as 20 which portion is fitted between the spaced webs of the adjacent diaphragms 30 3 and is extended so that an upper flange formed thereon as at 21 is made to rest solidly against the under surface of the top cover plate 4 at a point beneath the adjacent superposed casting 8, which point is in 35 the line of greatest compression from the superposed structure of the car. The portion 20 is formed of a plate 22 with lateral side flanges 23—23, which flanges are disposed to be fixed to the webs of the adjacent 40 diaphragms 3. Each of the flanges 23; also the plate 22, have their upper ends merging into the top flange 21 and their lower ends merging into the body portion of the side bearings and said plate and flanges are disposed 45 so as to follow said line of greatest compression and thus to materially assist the side vertical members or diaphragms of the bolster in withstanding the excessive stresses to which they are subjected as a 50 result of the natural tendency of the car body to tilt to one side or the other, which tendency is most apparent when the car is passing around a curve in the track.

55 The castings 8 are made hollow so as to reduce the weight thereof and the surrounding walls may be reinforced by any desirable form of webs or braces, but each casting is 60 preferably formed with a heavy rib as 24 disposed transversely of the bolster so as to rest in positive contact with the upper surfaces of the cover plate 4 at a point in the line of compression above the top flange of the portion 20 of the adjacent side bearing so as to more directly transfer the weight of 65 the superstructure to the side bearings.

Having thus described my invention, what I desire to secure by Letters Patent is:

1. In a car bolster, a vertical member, a bottom plate and a perforated side bearing member extending in one casting below said plate and above said plate and adapted to serve as an anchor for a tie rod projected therethrough from above.

2. In a car bolster, a vertical member, a bottom plate and a side bearing member having a perforated extension and extending in a single member above and below said plate and connected with said vertical member and adapted to serve as an anchor for a tie rod projected therethrough from above.

3. In a car bolster, vertical members, a bottom plate and side bearing members extending above and below said bottom plate and extending between and being secured to said vertical members.

4. A car bolster comprising vertical members and combined braces and side bearing members riveted to said vertical members and extending therebetween and therebelow.

5. In a car bolster, diaphragms, top cover plate and oblique brace members connected to said diaphragms terminating in side bearings.

6. In a car bolster, a side bearing member extending in one piece laterally below the bottom plate of said bolster and extending into said bolster to serve as a brace and connector and adapted to serve as an anchor for a tie rod projected therethrough from above.

7. A car bolster comprising vertical members, a horizontal member and a side bearing member connecting said vertical members and extending therebelow.

8. In a car bolster, vertical diaphragms and a side bearing member formed of a single flanged member of only slightly less depth than the maximum depth of said bolster and of greater depth than the minimum depth of said bolster, said side bearing member projecting laterally below said bolsters and being secured to said diaphragms.

9. In a bolster, center sills, diaphragms connected therewith, top and bottom cover plates and a single cast side bearing member connecting said diaphragms and extending below and lapping said bottom cover plate.

10. In a bolster, spaced struts, a center bearing casting connected thereto, diaphragms connected with said struts and casting and oblique members connecting said diaphragm and terminating in side bearings.

11. A bolster comprising vertical side walls, top and bottom cover plates and a side bearing member, said side bearing member being fixed to said bottom cover plate and having a portion extending between and secured to said side walls.

12. A bolster comprising a vertically disposed flanged member, a top cover plate fixed to one of the flanges of said member and a side bearing member fixed to the web of said member, said side bearing member having a portion resting in contact with said cover plate.
13. A bolster comprising a vertical member, a top cover plate fixed to said member and a side bearing member fixed to one of the vertical sides of said vertical member and having a portion resting in contact with said cover plate.
14. A bolster comprising a vertical member, a top cover plate, a superposed car body support upon said cover plate and a side bearing member fixed to said vertical member, said side bearing member having a portion resting in contact with said cover plate beneath said car body support.
15. A bolster comprising a top cover plate, a car body supporting member fixed upon the upper surface of said plate and a side bearing member disposed beneath said car body supporting member and in the line of greatest compression from the car body and being formed with a portion contacting with the under side of the said plate.
16. A bolster comprising top and bottom cover plates, a car body supporting member fixed upon the upper surface of said top cover plate and a side bearing member disposed beneath the plane of said bottom cover plate and being formed with a portion extending upwardly along the line of greatest compression from the car body, and contacting with the under side of the top cover plate beneath said car body supporting member.
17. A side bearing member for bolsters formed with a portion adapted to serve as an anchor receiving member for the car body.
18. A side bearing member for body bolsters formed with an upstanding portion adapted to sustain a part of the weight of the car body and with a portion adapted to serve as an anchor receiving member for the car body.
19. A bolster comprising spaced members, a side bearing member fixed to the under sides of said members and being formed with a portion disposed intermediate said members adapted to serve as an anchor receiving member for the car body.
20. A bolster comprising a longitudinal member, spaced struts, car body supports disposed upon opposite sides of said struts and being adapted to receive the entire weight of the adjacent end portion of the car body and side bearing members formed with portions projecting into proximity with said car body supports and being adapted to partly sustain said car body supports.
21. In a car bolster having side walls, a side bearing attached thereto and provided with a perforated flange adapted to receive the end of a tank band extending through said bolster and also provided with an upward extension projecting into the interior of the bolster, said upward projection being adapted to reinforce the bolster above the side bearing by connection with said side walls.
- In witness whereof I have hereunto set my hand in the presence of two witnesses.
